[57] CLAIM

The ornamental design for a magnetizable rotor for liquid treatment apparatus, as shown and described.

DESCRIPTION

FIG. 1 is a perspective view from above one side and one end of a magnetizable rotor embodying my new design;

FIG. 2 is a side elevation;

FIG. 3 is a plan view;

FIG. 4 is an underneath view; and

FIG. 5 is an end elevation.

FIG. 1.

FIG. 2.

FIG. 3.

FIG. 4.

FIG. 5.
